UNITED STATES PATENT OFFICE.

FREDERICK SHRIVER, OF GEORGETOWN, SOUTH CAROLINA.

HEAT-RETAINER.

1,303,122.

Specification of Letters Patent.

Patented May 6, 1919.

Application filed February 11, 1919. Serial No. 276,304.

To all whom it may concern:

Be it known that I, FREDERICK SHRIVER, a citizen of the United States, residing at Georgetown, in the county of Georgetown 5 and State of South Carolina, have invented new and useful Improvements in Heat-Retainers, of which the following is a specification.

This invention relates to fluid fuel burners, or more particularly those in which the fluid either is gas or is converted into gas at the point of its consumption; and the invention has reference to flame deflectors whereby the heat is reflected or deflected 10 onto the retort so as to conserve the temperature thereof. In burners of this character, and more particularly those used on hand lamps, the mantles become broken repeatedly and need constant attention and replacing. It is the purpose of the present invention to retain the heat by means of a reflector in the shape of a hood or bell standing over the mantle (if one be employed) and preferably mounted on the bend of the 15 retort, whereby the flame rising from the mantle or other burner is to a degree reflected downward and its heat conserved and utilized. The invention consists broadly in this idea, and specifically in the details 20 in carrying it out, all as hereinafter more fully described and claimed and as shown in the drawings wherein:—

Figure 1 is a side elevation of a lamp of appropriate type with this invention applied.

Fig. 2 is a central longitudinal section through the heat retainer or bell.

Fig. 3 is a perspective detail of the means within the bell for mounting it on the bend of the retort.

The lamp to which my invention applies is typically illustrated herein as comprising a reservoir or tank T, a retort R rising therefrom and given an upward curve so that it is carried thence again downward, and a burner proper which in this case is a mantle M standing beneath the bend of the retort. Air is usually supplied at A from a bulb or other device connected by a short 45 section of flexible hose to a nipple as shown. I do not wish to be limited in any respect to the type or construction of the lamp, further than that its retort shall have the upward bend referred to and that the flame or 50 blaze should be beneath said bend, but if a mantle is used as illustrated at M, my heat

retainer serves also as a protector for the mantle as experience has proven.

Coming now to the details of the invention itself, the retainer is in the form of a sheet metal hood or bell having some of the general characteristics of the heat bells formerly employed over gas burners to prevent the burning of the ceiling, although in the present case it is mounted directly on the retort, is much nearer the burner or flame and may in fact inclose the upper portion of the mantle, and it is by preference of metal so that it conserves and retains the heat for purposes which will appear. This bell, indicated generally by the numeral 1, is composed of outer and inner walls 2 and 3 as seen in Fig. 2, slightly spaced from each other, and pierced with openings or perforations which are staggered with relation to each other and out of register in the two walls. These openings 4 may be of any shape and appropriate size, and their number and exact disposition are matters of no moment but will depend to an extent upon the character of the lamp and burner. The outer and inner walls may join each other near the lower edge 5 of the burner, but are separated slightly at the upper portions of its side walls and along the top. The heat retaining bell is of a size proportionate to the device to which it is applied, and is preferably oval and provided on its top with a ring-shaped handle 6 into which a suitable tool may be inserted when it is to be removed or replaced while hot.

The sole support for this bell is a clip or clasp as best illustrated in Fig. 3, the same being made up of two complementary metallic members secured within the bell by means which permit the relative adjustment of said members for a purpose to appear. One member has a flat body 10 longitudinally slotted as at 11 and substantially rectangular in contour, a pair of depending fingers 12 at one end, and a tongue 13 depending from the other end and bent transversely into the shape of a trough of practically semi-circular cross-section. The other member is made in the same manner excepting that the tongue 14 is perhaps a little longer, and otherwise I have given its parts the same reference numerals. In assembling these members, the body of one is laid over the body of the other with the slots in registry, and a screw or bolt 15 passes through the registering slots and is

engaged with the inner or lower wall of the bell, and when this screw is tightened up or the nut on the bolt is tightened up, the parts are held in adjusted position and both 5 parts or members are held within the bell. At this time the tongue on one member stands between the fingers on the other, and both tongues are deflected or bent slightly outward whereas the fingers depend practically 10 vertically from the plate or members. The adjustment permitted by the slots is obviously for the purpose of separating the grooved or curved tongues a greater or lesser distance, according to the size of the 15 bend at the top of the retort R, and said tongues are also made semi-circular for the obvious purpose of causing them to fit or wedge rather tightly on the pipe of which the retort is made. Thus if the members 20 of this clamp or clasp are made of spring metal, its tongues will bite on the metal of the bent retort and the entire bell will be supported thereby in the position in which it is placed.

25 I find that the use of a heat retainer of this character on a lamp of substantially the type illustrated is quite advantageous and effective as first above set forth, and the breakage of mantles M is much less than 30 with such lamps where a retainer is not applied. Ordinarily when it is desired to adjust or replace the mantle, the parts become cold or cool during the operation and vaporization is not quickly resumed, and the 35 result is that the user is compelled to heat the burner when the mantle is relighted, unless he can make the substitution or repairs very quickly. With the use of my addition, even when it is necessary to entirely remove it 40 in order to effect a change of parts, this can be done by inserting a metal element into the ring or handle and lifting it out of place, then the repairs or change can be made, and finally the retainer or bell can be replaced 45 without much loss of its heat, with the result that vaporization is readily resumed. In many cases where the device is a torch, it is possible to replace the mantle without 50 removing the bell at all. In all cases the double walls of the bell, and the fact that 55 they are of metal, causes it to retain the heat for a considerable time; and the intimate metallic contact of the clasp with the retainer and the tongues of the clasp with the retort, conducts the heat of the bell into the retort to a considerable extent. I do not wish to be limited to the sizes and shapes

of parts, nor to details further than set forth in the following claims.

What is claimed as new is:—

1. The herein described heat retainer for lamps, torches, and the like whose retort has an upward bend above the burner, the same consisting of a bell composed of spaced metallic walls provided with perforations 65 out of registry with each other, and a clasp within the inner wall for detachable engagement with the bend of said retort.

2. The herein described heat retainer for lamps, torches, and the like whose retort 70 has an upward bend above the burner, the same comprising a bell of oval shape made up of inner and outer walls in contact with each other around their lower edges at the mouth of the bell and elsewhere slightly 75 spaced from each other and pierced with non-registering openings, means for removably mounting it on the bend, and a ring-shaped handle at the top of the bell.

3. The combination with a fluid fuel lamp 80 having a retort provided with a bend arched over its burner; of a heat retainer comprising a metallic bell of a size to inclose the upper portion of the retort, and a clasp composed of two members mounted within 85 said bell adjustably with reference to each other, and each having a depending curved tongue for engagement with one side of said arch.

4. The combination with a fluid fuel lamp 90 having a retort provided with a bend arched over its burner; of a heat retainer comprising a metallic bell of a size to inclose the upper portion of the retort, a clasp made up of two complementary members each including 95 a flat body having a longitudinal slot and a channeled tongue depending from one end of the body, said bodies being overlapped and their slots in register, and fastening means passing through said slots and 100 taking into the bell.

5. A bell for use on a hot bent pipe comprising a body of inverted cup-shape, a fastening device within the center of said body, and a clasp in two members each having a flat body engaged by said fastening device, a pair of spaced fingers depending from one end of the body, and a channeled tongue depending from the opposite end of the body between the fingers of the other 110 member and adapted to engage the bend of said pipe.

In testimony whereof I affix my signature,
FREDERICK SHRIVER.
